UNITED STATES PATENT OFFICE.

HENRY C. REESE, OF MOUNT PROSPECT, ILLINOIS.

POWER REGULATOR.

Application filed May 1, 1925. Serial No. 27,275.

This invention relates to new and useful improvements in automatic power regulators and more particularly to an improvement over my application filed December 1, 5 1923, bearing Serial No. 678,074. The main object of my invention is the provision of a new and improved pulley for automatically regulating the driving power of the engine for operating the various types of machines 10 used in grain threshing or separating, corn shredding, ensilage and the like.

Another object of my invention is the provision of a new and improved take-off pulley adapted to be used on engines for 15 driving threshing machines and the like whereby the speed of the engine may be automatically controlled according to the load applied to the take-off pulley. The construction of the device is such that the throttle valve, controlling the supply of fuel to 20 an internal combustion engine, will be automatically opened to permit supply of fuel to the engine when the load is applied to the take-off pulley and the throttle valve will 25 be automatically operated to decrease the supply of fuel to the engine commensurate with the decrease in the amount of load applied to the take-off pulley whereby the engine will not be over-supplied nor under- 30 supplied during operation thereof.

Another object of my invention is the provision of a novel construction used in connection with the power take-off pulley which is operatively connected to the throttle 35 of the engine and the governor whereby the throttle and governor will be controlled by the applied load to the take-off pulley.

With the above and other objects in view, my invention consists in the novel features 40 of construction and the combination and arrangement of parts to be hereinafter more fully described, pointed out in the claims and shown in the accompanying drawings, in which:

Fig. 1 is a detailed plan view of the driving mechanism of an engine illustrating my device applied thereto,

Fig. 2 is a detailed elevation illustrating the connection to the throttle and governor 50 of the engine, parts thereof being broken away and illustrated in cross section,

Fig. 3 is a side elevation of my improved mechanism applied to the power take-off pulley and driving shaft,

Fig. 4 is a transverse sectional view on the 55 line 4—4 of Fig. 3,

Fig. 5 is a transverse sectional view on the line 5—5 of Fig. 4,

Fig. 6 is a detailed sectional view taken through the line 6—6 of Fig. 3,

Fig. 7 is a detailed section taken through the connection between the throttle and governor illustrating the connection in one position,

Fig. 8 is a similar view illustrating the 65 connection in an opposite position from that shown in Fig. 7,

Fig. 9 is a transverse section on the line 9—9 of Fig. 7, and

Fig. 10 is a detailed transverse section on 70 the line 10—10 of Fig. 1.

In the drawings, the number 1 indicates the usual take-off pulley which is rotatably mounted upon the driving shaft 2 driven by a driving shaft 3 which is connected to the 75 engine by any suitable clutch mechanism. In the present instance I have illustrated suitable mechanism associated with the pulley 1 for controlling the throttle valve 4 which controls the fuel supply to the engine.

Mounted upon the driven shaft 2 and arranged within the pulley 1 is a disc 5, Fig. 4, which has formed thereon arms 6, Fig. 3. The ends of the arms 6 define arms 7 and 8. The arms 8 carry suitable pins 9 which engage within one end of the coil springs 10, Fig. 3, the other ends of said coil springs being mounted upon suitable pins 11 carried by blocks 12 which are attached as at 12' to the flange 1' of the pulley 1, Fig. 3.

The disc 5 is keyed to the shaft 2 as shown at 13 for rotation therewith. The arms 7 are provided with transverse openings and slidable therethrough are the rods 14 the inner ends of which are universally connected with the arms 15 and project laterally from the rotative sleeves 16. The sleeves 16 are rotatably mounted upon the rods 17 having one of their ends attached to the pulley 1 as shown at 18 while the other or inner 100 ends extend into suitable recesses 19 in the hub 20 of the pulley.

Extending laterally from the sleeve 16, and at right angles with respect to the arms 15, are links 21, Fig. 3, which are preferably formed at the inner ends of the sleeve 16. The links 21 carry pins 22, Fig. 5, which engage within slots 23 formed in the

arcuated plates 24, Fig. 4, for rotation therewith, by free and slideable movement longitudinally thereof. This longitudinal movement of the plates 24 is permitted by recesses 24', Fig. 4, formed in the plates 24 for receiving the keys 20' when the plates move longitudinally of the shaft 20.

From the above it will be apparent that when the load is applied to the pulley 1 the 10 arms 8 will press the springs 10 to a certain extent causing the arms 7 to move toward the arms 15 and through the universal connection 25 the arms 15 will be moved laterally rotating the sleeves 16 and imparting a 15 lateral movement to the arms 21 in a direction toward the outer side of the pulley whereby to slide the arcuate plates 24 outwardly. Mounted upon the outer end of the hub 20 and connected to the arcuate plates 20 24 is a collar 26 which is connected to the plates 24 by means of a split ring 27 which is bolted to the collar 26 as shown at 28. Thus, when the plates 24 are moved longitudinally upon the hub 20 the collar 26 will 25 be moved in the same direction.

The collar 26 includes oppositely disposed lugs 29 which are connected to a yoke 30, Figs. 1 and 3. This yoke 30 provides an arm 31, Fig. 1, formed as an integral part 30 of a bell crank 31' pivotally supported by the frame 32' of the internal combustion engine, (not shown), as indicated at 32. The other arm 62 provided by the bell crank 31' has formed thereon a sleeve 33 slidably receiving one end portion of a control rod 34. Mounted upon this end portion of the control rod, on opposite sides of the sleeve, are cushioning springs 35, Fig. 1. These cushioning springs are adjusted upon this end 40 portion of the control rod through the medium of nut members 36.

The rod 34 is pivotally connected at its opposite end portion to a link 37. The link 37 also is pivotally connected with the rod 45 40. The outer end of the rod 40 is provided with a downturned end 41 and connected to this downturned end 41 is a rod 42 which is loosely mounted in the sleeve 43. This lever 43 is pivotally carried, through 50 the medium of a pintle 45, by a substantially U-shaped bracket 44. To this pintle 45 are pivotally connected, at the lower end portions, parallel bars 46 which extend upwardly through a slot 47 into a housing 48. This housing 48 is a tube 49 having oppositely disposed parallel slots 50 in which the upper end of the bars 46 move.

Attached to the upper ends of the bars 46 at spaced points are the rods 51 and 52. The 60 rod 51 has connection to a crank arm 52' of the throttle valve 4. The outer end of the rod 52 is operatively connected to a bell crank 53' pivotally supported by the frame 32' of the engine, as at 54'. The outer end of 65 the arm 55', of this bell crank, operatively en-

gages in an angular slot 31 formed in a sleeve 56' of the governor mechanism 53. This sleeve 56' is mounted for longitudinal movement on a drive shaft 57' included as a part of the governor mechanism 53. Movement 70 of the sleeve 56' is urged by the governor mechanism weight arms in a manner well known to those skilled in the art.

The U-shaped bracket 44 is suspended for swinging movement upon the plate 54 attached to the housing 47, said bracket being suspended by means of the rods 55 the lower ends of which are pivotally connected to the side walls of the bracket while the upper ends are pivotally connected in spaced relation at the plate 54. A coiled spring 56 is mounted upon the rod 42 and disposed between the sleeve 43 and the downturned end 41 whereby when the collar 26 is moved outwardly relative to the pulley 1 the tension of the spring 56 is sufficient to cause the bracket 44 to swing upon its suspension to move the rods 51 and 52 in longitudinal directions for reasons hereinafter set forth. A suitable stop member 57 may be attached 80 to the engine in any suitable position whereby the same will be engaged by the bracket 44 when the throttle is in a fully opened position and whereby the further movement of the collar 26 will cause the spring 56 to be 85 placed under compression but in no manner imparting further movement to the rods 51 and 52.

In Figs. 1 and 10 I have illustrated a signal device adapted to be used in connection with the regulator whereby to indicate to the operators of a machine being driven by the engine to ascertain when the same is being overloaded. This indicator includes a frame 58 having a graduated bar 59 upon 105 one side provided with a longitudinal slot 60 in which is slidably mounted an indicator 61. The outer end of the arm 62 of a bell crank 31 is provided with the off-set portion 63 adapted to engage one side of the indicator 61 to move the same within the slot 60 upon movement of the angle bar 31 for opening the throttle upon application of a load to the pulley 1.

Mounted upon the frame 58 is the bracket 115 64 which is adjustable by means of the clamping plate 65 and screw bolts 66. This bracket supports the rotatable rod 67 upon the upper end of which is a signal plate 68 and attached to the lower end of the rod 67 120 are the angularly disposed arms 69 and 70. As illustrated, in Fig. 1 the signal device plate 68 is arranged parallel with the frame 58 indicating that there is a normal load being applied to the pulley 1 but as the load 125 increases, the pin 71 carried by the arm 69 moves along the arm 69 actuating the arm 70 thus rotating the rod 67 and moving the signal plate transversely of the frame 58 whereby this plate will be readily viewed by 130

the operators of a machine being driven by the engine and indicate to them that the machine is being loaded too heavily so that the load may be decreased. The graduations on the bar 59 will also indicate the greatest amount of horse power used in operating the machine to which the engine is connected, as the indicator 61 will remain stationary after being adjusted on the slot by means of the off-set portion 63 of the arm 64.

The operation of the combination and arrangement of parts as above described is as follows:

When the collar 26 is moved in an outward direction of the pulley 1 by movement of the plates 24 the bell crank 31' is pivoted about its pivot 32 and urges movement to the rod 34 in the direction indicated by the arrow in Fig. 1. This movement of the rod 34 in this direction acts upon the bracket 44 and swings the bracket toward the stop member 57 upon its suspension. When this bracket 44 is swung in said direction it acts upon the bars 46 to pivot these bars in a direction to open the throttle valve to increase the supply of fuel to the engine and commensurate with the application of the load on the pulley 1.

It is important to note that the bars 46 pivot about a point indicated at 46' which point is the point of connection between the operating rod 52 and the bars 46. When the bars 46 are pivoted in this direction the operating rod 52 is held against longitudinal movement by the bell crank 53' engaging the sleeve 56'. The bars 46 in pivoting about this point 46' move the operating rod 51, in the direction indicated by the arrow in Fig. 7 to open the throttle valve for reasons herein set forth.

After the throttle valve 4 is opened by action of the pulley 1 to increase the supply of fuel to the internal combustion engine the governor mechanism 52 serves to govern the supply of fuel to the engine whereby to permit a uniform speed of rotation to the pulley 1. This is accomplished in the following manner:

To illustrate the operation of the governor mechanism 53 let it be considered that the pulley 1 is rotating at approximately 500 R. P. M. and due to the overcoming of the load on the pulley 1 by the power of the internal combustion engine when the throttle valve is opened by operation of the pulley 1 the R. P. M. of the pulley slightly increases. The governor mechanism 53, through the medium of the governor mechanism weight arms 58 will act upon the sleeve 56' and move this sleeve 56' in a downward direction longitudinally of the driven shaft 57'. As this sleeve 56' moves in this direction it pivots the bell crank 53' about its pivot 54' and moves the operating rod 52 in a direction indicated by the arrow

in Fig. 7 of the drawings. As this operating rod moves in this direction it acts upon the bars 46 and pivots these bars about the pivot 45 to move the operating rod 51 in an opposite direction to that indicated by the arrow in Fig. 7 of the drawing to close the throttle valve 4 so as to supply a sufficient amount of fuel commensurate with the application of the load upon the pulley 1. After the throttle valve 4 has been acted upon through the operation of the governor mechanism 53, should the R. P. M. of the pulley fall below 500 R. P. M. the throttle valve 4 will be again acted upon by operation of the pulley 1 through the medium of the rod 34 and its associated parts.

It will be apparent from the foregoing that I have provided an improved power regulator whereby the fuel feed to the engine will be automatically controlled thru the weight of the load applied to the take-off pulley as under normal load the pressure of the arms 8 against the springs 10 will drive the pulley 1 but as soon as the load is applied thereto the springs 10 will be placed under compression causing the arms 7 to actuate the arms 15 and rotate the sleeve 6 which movement will in turn move the collar 26 laterally on the hub 20 of the pulley and impart movement to the connection with the throttle and governor.

While I have shown and described the preferred form of my invention, it will be obvious that various changes in the details of construction and in the proportions may be resorted to for successfully carrying my invention into practice without sacrificing any of the novel features of the same or departing from the scope of the appended claims.

Having thus described my invention, what I claim is:

1. A power regulator including a drive shaft, a disc keyed to the same, a pulley loosely mounted upon the shaft, cooperative yieldable connection between said disc and pulley whereby to rotate said pulley, means whereby to vary the relative position and of the cooperative means upon the application of a load to the pulley beyond a predetermined degree and means actuated by the variation of the cooperative means whereby to impart movement to the throttle and governor mechanism controlling the speed of the drive shaft.

2. A power regulator including drive shaft, a disc keyed thereto, a pulley loosely mounted upon the shaft adjacent the disc, yieldable cooperative means connecting the disc and the pulley for imparting movement to the pulley simultaneously with the movement of the disc, said means permitting movement of the pulley relative to the drive shaft and disc upon the application of a load to the pulley beyond a predetermined

- degree, and pivoted angle bar adjacent the pulley, means forming a connection between the one end of the bar and the yieldable connection for imparting rocking movement 5 to said bar upon movement of the pulley relative to the disc and additional means forming connection between the other end of the bar and the throttle and governor for controlling the speed of the drive shaft.
- 10 3. A speed regulator including a drive shaft, a disc keyed thereto, a pulley loosely mounted upon the shaft adjacent the disc, an abutment block carried by the pulley and arranged in opposed relation to the 15 same, oppositely disposed arms carried by the disc, yieldable means between the one end of the said arms and the abutment blocks whereby rotation of the disc will impart rotation to the pulley, said yieldable 20 means being placed under tension upon the application of a load of the pulley beyond the predetermined degree imparting movement to the pulley relative to the disc and

cooperative connection between the other ends of said arms and a throttle and governor relative to the disc will actuate the throttle and governor for controlling the speed of the shaft. 25

4. A power regulator including a drive shaft, a disc keyed thereto, a pulley loosely mounted on the shaft and adjacent the disc, oppositely disposed abutment blocks carried by the pulley, arms carried by the disc, spring means between the one end of said arms and the abutment blocks whereby rotation of the disc will impart movement to the pulley, said spring being compressed upon the application of a load to the pulley of a predetermined degree, a slidable collar upon the hub of the pulley and operative connection between the arms on the disc and the collar whereby to impart sliding moving of the collar upon the movement of the pulley relative to the disc. 30 35 40

In testimony whereof I affix my signature.
HENRY C. REESE.
